Des. 186,702
Patented Nov. 17, 1959

186,702

DESK BASE FOR A WRITING INSTRUMENT

William E. L. Bunn, Fort Madison, Iowa, assignor to W. A. Sheaffer Pen Company, Fort Madison, Iowa, a corporation of Delaware

Application August 6, 1958, Serial No. 52,078

Term of patent 14 years

(Cl. D74—1)

FIG. 1

The dotted line showing of a pen in Figure 3 is for illustrative purposes only.

I claim:

The ornamental design for a desk base for a writing instrument, substantially as shown and described.
